UNITED STATES PATENT OFFICE.

HORACE WYMAN, OF WORCESTER, MASSACHUSETTS, ASSIGNOR TO CROMPTON & KNOWLES LOOM WORKS, A CORPORATION OF MASSACHUSETTS.

WEFT-REPLENISHING LOOM.

1,089,369.

Specification of Letters Patent. Patented Mar. 3, 1914.

Application filed June 6, 1912. Serial No. 702,030.

To all whom it may concern:

Be it known that I, HORACE WYMAN, a citizen of the United States, residing at Worcester, in the county of Worcester and 5 State of Massachusetts, have invented certain new and useful Improvements in Weft-Replenishing Looms, of which the following is a specification.

My invention relates to automatic weft replenishing looms of the type shown and described in the Letters Patent, No. 1,080,748, in which a stationary magazine is used with 10 four guide-ways or compartments for superposed bobbins or filling carriers, at one end 15 of the loom, and shifting or change shuttle boxes at the other end of the loom, for shuttles with fillings of different colors or characters, which correspond to the filling in the compartments of the magazine.

20 My invention more particularly relates to weft replenishing looms of the type referred to, for weaving blankets or similar fabrics, which have a border woven thereon, with filling ordinarily of three different colors 25 or characters, and the center portion of the blanket plain, with a filling of one color or character.

The object of my invention is to improve 30 upon the type of weft replenishing looms referred to, and more particularly to provide two supplemental or extra compartments or guide-ways in the magazine, which have their lower openings leading to the 35 same general discharge opening, and holding and releasing devices for said extra compartments or guide-ways, which release the bobbins at the proper time, to deliver a bobbin to the cradle or retaining support of one of the other compartments, although only 40 a single one may be used if desired.

The magazine shown in the drawings is 45 provided with three compartments, which hold bobbins or filling carriers of the same color or character for the plain center portion of the blanket to be woven.

I have shown and described in this instance a magazine with six compartments or guide-ways for superposed bobbins or filling carriers; three of the compartments are 50 termed primary compartments, and are used for bobbins or filling carriers which have filling thereon which correspond with the filling in the three change shuttles for weaving the border on the blanket or other fabric. 55 The plain center portion of the blanket or

other fabric is woven by the fourth shuttle, which has a bobbin with filling thereon which corresponds with the filling in the bobbins or filling carriers in the three other compartments or guide-ways in the magazine. One of the three compartments, in 60 this instance the fourth compartment of the magazine, is provided with the usual rocking cradle or support which releases the bobbin or filling carrier for its passage to the 65 discharging end of the magazine, in the usual way. The two supplemental or extra compartments or guide-ways are provided with retaining and releasing devices, which are adapted to release a bobbin and to deliver the same to the cradle or support of 70 the fourth compartment, after said fourth compartment has been emptied of its bobbins or filling carriers.

The cradle or rocking support is operated 75 in the usual way to release a bobbin, which takes the place of the practically or substantially exhausted bobbin, with the same color or character of filling for the plain center 80 portion of the blanket, in said shuttle, and said new bobbin is transferred into the shuttle by the usual transferring mechanism.

My invention consists in certain novel features of construction of my improvements 85 as will be hereinafter fully described.

I have only shown in the drawings a detached portion of the magazine of the class referred to, with my improvements combined therewith, sufficient to enable those skilled 90 in the art to understand the construction and operation thereof.

Referring to the drawings.—Figure 1 is an inner end view of a detached portion of a magazine of the type referred to, with my improvements combined therewith. Fig. 2 95 is a plan view of some of the parts shown in Fig. 1, and a section, on line 2, 2, same figure, looking in the direction of arrow a, Fig. 1. Fig. 3 is a section, on line 3, 3, Fig. 2, looking in the direction of arrow b, same figure; showing the lower portion of the inner end of the magazine, with bobbins for the plain weave in their compartments. Fig. 4 corresponds to Fig. 3, but shows a different position of the rocking supports, and a 100 bobbin dropped to the discharging end of the magazine. Fig. 5 is a section, on line 5, 5, Fig. 2, looking in the direction of arrow c, same figure, and showing the tips of the bobbins in their respective compart- 110

- ments, and, Fig. 6 corresponds to Fig. 5, but shows the rocking supports operated, for a bobbin to be dropped to the discharging end of the magazine.
- 5 In the accompanying drawings, 1 is a stationary stand mounted on the breast beam of the loom, not shown. The stand 1 has rigidly connected thereto the inner end 2 of the magazine, which carries, on transverse 10 rods 3, the outer end 4 of the magazine, in the usual way. The magazine has in this instance, four vertically extending compartments or guide-ways 2' for the heads of the bobbins 5, and 4' and 4' for the tips 5' of the bobbins 5, respectively, which bobbins, in this instance, correspond in color or character to the bobbins which are held by the fourth compartment 2', and 4', respectively. The two extra compartments are connected at their lower ends, and are adapted to drop a bobbin 5 from each compartment into the same chute or incline, which leads the bobbins to the cradle 6, which is adapted to retain, and to release the bobbins from the fourth compartment of the magazine in the usual way. The cradle 6 is operated in the usual way by the vertically moving bar 7, at the left in Figs. 1 and 2. Said bar is provided in this instance with a lug or ear 7', to which is pivotally connected 20 the upper end of a downwardly extending connector 12; the lower end of said connector 12 is pivotally connected to an arm 13, which has its hub 13' secured on a transverse shaft 14, which, in this instance, is 25 loosely mounted in bearings 2''' and 4''' at the inner and outer ends 2 and 4, respectively, of the magazine. The transverse rod 14 has in this instance secured thereon retaining and releasing devices for the bobbins 30 which are held in the supplemental or extra compartments or guide-ways of the magazine. These retaining devices consist in this instance of a lever 15 for the heads, and a lever 16 for the tips 5' of the bobbins 5, see 35 Figs. 3 to 6, inclusive. As clearly shown in the drawings, the shape of the levers 15 and 16 are so formed, that they are adapted to hold and to release the bobbins.
- 40 The holding and releasing mechanism consists of a rocking support or cradle 6, pivotally mounted at the lower part of the magazine. A pin 6' extends within a curved slot 7' in the lower portion of the vertically moving bars 7, which are loosely guided at the end of the magazine 2. Each bar 7 is provided with two projections 7'', which are adapted to extend in the path of and to be operated by the fingers 8, which have their 45 hubs 8' secured upon a horizontal sliding rod 9, which is loosely mounted in bearings 2''' on the magazine 2. The end of said rod 9 has a collar 10 secured thereon, which has an annular groove 10', which is adapted 50 to receive a stud on a lever, not shown, which, through the raising and lowering of the shuttle boxes on the opposite end of the loom, will communicate, through intermediate connections, not shown, a sliding motion to the rod 9 and to the fingers 8 thereon. The side extension 8'' on the hubs 8', extends loosely into a notch on a lever 11, which, through its up and down movement, 55 will impart a rocking motion to the extension 8'' and the fingers 8, to cause the up and down movement of a vertically extending bar 7, and the rocking of a cradle 6.
- 60 All of the above mentioned parts, except the special construction of the magazine, 65 may be of any usual and well known construction, and as fully shown and described in the Letters Patent No. 1,030,748, above referred to.
- I will now describe my improvements.
- I provide the stationary magazine, having 70 the four usual compartments or guide-ways, with two supplemental or extra compartments or guide-ways 2'' and 2'' for the heads of the bobbins 5, and 4'' and 4'' for the tips 5' of the bobbins 5, respectively, which bobbins, in this instance, correspond in color or character to the bobbins which are held by the fourth compartment 2', and 4', respectively. The two extra compartments are 75 connected at their lower ends, and are adapted to drop a bobbin 5 from each compartment into the same chute or incline, which leads the bobbins to the cradle 6, which is adapted to retain, and to release the bobbins from the fourth compartment of the magazine in the usual way. The cradle 6 is operated in the usual way by the vertically moving bar 7, at the left in Figs. 1 and 2. Said bar is provided in this instance with a lug or ear 7', to which is pivotally connected 80 the upper end of a downwardly extending connector 12; the lower end of said connector 12 is pivotally connected to an arm 13, which has its hub 13' secured on a transverse shaft 14, which, in this instance, is 85 loosely mounted in bearings 2''' and 4''' at the inner and outer ends 2 and 4, respectively, of the magazine. The transverse rod 14 has in this instance secured thereon retaining and releasing devices for the bobbins 1 90 which are held in the supplemental or extra compartments or guide-ways of the magazine. These retaining devices consist in this instance of a lever 15 for the heads, and a lever 16 for the tips 5' of the bobbins 5, see 1 Figs. 3 to 6, inclusive. As clearly shown in the drawings, the shape of the levers 15 and 16 are so formed, that they are adapted to hold and to release the bobbins.
- The up and down movement of the vertically moving rod 7 will impart a rocking motion to the cradle 6, and also communicate at the same time a rocking motion to the devices or levers 15 and 16, which in one position, as shown in Figs. 3 and 5, will hold the bobbins in their respective supplemental or extra compartments or guide-ways, and as the cradle 6 is rocked to drop a bobbin to the discharging end of the magazine, as shown in Figs. 4 and 6, the devices 15 and 16 are moved to the position shown, coöperating to release the bobbins 5 from their supplemental compartments.
- If all of the bobbins 5 are dropped from the fourth compartment 2' and 4', the next bobbin from the supplemental compartment 4'' will take its passage to the cradle 6, to drop into said cradle, and be delivered at the next movement thereof to the discharging end of the magazine, until all of the bobbins

are successively delivered to the cradle 6, and released therefrom in the usual way, all as will be fully understood by those skilled in the art.

5 It will be understood that the details of construction of my improvements may be varied if desired.

Instead of the fourth compartment, and the supplemental compartments being combined with other compartments being combined with other compartments for bobbins having fillings of different colors or characters, this fourth compartment, and the supplemental compartments are equally well adapted to be used in looms using one color only, and without the shifting shuttle boxes for shuttles with fillings of different colors, or the compartments of the magazine for bobbins of corresponding colors. The fourth compartment, equally well with the other 15 three, may be termed a primary compartment, in its combination with the supplemental compartments.

Having thus described my invention, what I claim as new and desire to secure by Letters Patent is:—

1. In a weft replenishing loom, a magazine having a primary compartment for superposed filling carriers, a rocking support or cradle upon which the lowest of the superposed filling carriers rests, to retain said filling carriers, and also to release the lowest of said filling carriers from said compartment, and means for operating said support or

cradle, and one or more supplemental compartments for superposed filling carriers, 35 and retaining and releasing device for the filling carriers in said supplemental compartments, and means for operating said retaining and releasing device, to allow the filling in a supplemental compartment to 40 pass into the adjoining primary compartment, upon the exhaustion of filling in said primary compartment.

2. In a weft replenishing loom, a magazine with a plurality of primary compartments 45 for superposed filling carriers, each compartment having filling of different colors or characters, retaining and releasing devices for said compartments, and one or more supplemental compartments for superposed filling carriers having filling of the same color or character as the filling in one of said primary compartments, and retaining and releasing devices for the filling carriers in said supplemental compartment or 55 compartments, and means for operating said retaining and releasing devices, to allow the filling carriers in a supplemental compartment to pass into the adjoining primary compartment, upon the exhaustion of the 60 filling carriers in said primary compartment.

HORACE WYMAN.
